UNITED STATES PATENT OFFICE.

THOMAS S. HATHAWAY, OF DECATUR, ILLINOIS.

MATCH-SAFE.

Specification forming part of Letters Patent No. 58,253, dated September 25, 1866.

To all whom it may concern:

Be it known that I, THOMAS S. HATHAWAY, of Decatur, Macon county, State of Illinois, have invented a new and Improved Match-Safe; and I do hereby declare that the following is a full, clear, and exact description thereof, which will enable others skilled in the art to make and use the same, reference being had to the accompanying drawings, forming part of this specification, in which—

Figure 1 represents a vertical section of this invention, taken in the plane indicated by the line $x x$, Fig. 2. Fig. 2 is a plan or top view of the same.

Similar letters of reference indicate like parts.

This invention relates to a match-safe the receiving-chamber of which is provided with an inclined bottom over which the matches roll or slide down toward a vertical slide. This slide is provided with a shoulder just wide enough to receive one match, and on being raised the match resting on said shoulder is also raised, and its end is brought in contact with a friction-spring which is fastened on the top of the match-safe, and which is so situated that by its action the match carried up by the slide is brought in a vertical position, and at the same time the charged end or head of said match is clamped between the edge of the slide and the friction-spring, so that by pulling it out quick it will ignite, and that one match after the other can thus be raised and ignited in quick succession.

A represents a chamber, which is intended to receive the matches, and which is just wide enough to correspond to the length of the matches which it is to hold. The bottom of this chamber is inclined, so that the matches placed thereon will slide or roll down toward the slide B. This slide moves freely up and down in front of the chamber A, being held between suitable guides, and it is provided with a shoulder or recess, a , just wide enough for one match to lodge upon.

The width of the slide B is somewhat less than the length of the matches in the cham-

ber, and these matches are all placed into the chamber with their heads or fire ends in one and the same direction, so that the head of the match resting on the shoulder a will project beyond the edge of the slide B, as shown in Fig. 2 of the drawings.

When the slide is raised, the head of the match, resting upon the shoulder a , is brought in contact with a friction-spring or rasp-bar, b , which is fastened down to the top of the chamber A, so that its roughened end comes close up to the edge of the slide. On striking the edge of the rasp-bar the match is raised to a vertical position, so that it can be conveniently taken hold of and pulled out. In pulling it out quick the friction of the rasp-bar causes the match to ignite, and no further friction-surface is required.

The rasp-bar b is adjustable on the top of the chamber A, so that its friction-surface can be made to bear with more or less power on the head of the match.

The chamber A may also be provided with a sliding partition or cut-off, c , whereby the quantity of matches pressing on the slide can be diminished and a correct operation of the safe is insured.

By this safe the matches are inclosed, so that nobody can get out more than one at a time, and the matches are made to go off by the very act of withdrawing them from the safe, so that no further friction-surface is required and the walls are saved from injury.

What I claim as new, and desire to secure by Letters Patent, is—

The vertical slide B, with its shoulder or recess a , in combination with the receiving-chamber A and friction-spring b , constructed and operating substantially as and for the purpose described.

The above specification of my invention signed by me this 16th day of February, 1866.

THOS. S. HATHAWAY.
